SAFETY CATCH.

Application filed November 21, 1925. Serial No. 70,606.

This invention relates to an improved construction of safety catch for pin stems, more particularly adapted to be applied to jewelry and the like; and the invention has for its object to provide an improved construction of body member and keeper for the catch, in which the body member is provided with a trunnion on which the keeper member is rotatably mounted, the inner face of one of the side ears of the body member being grooved and the keeper being provided with a member or portion extending into said groove to increase the inner and outer bearing surfaces of the keeper and to support the keeper against spreading and becoming disengaged from its mounted position in the body when under an excessive opening strain.

A further object of the invention is the provision of a peripheral bar bridging the space between the ears of the body member and the provision of a plurality of peripheral radial protuberances on the keeper located so as to cooperate with the bar to releasably retain the keeper in either open or closed position.

With these and other objects in view, the invention consists of certain novel features of construction, as will be more fully described, and particularly pointed out in the appended claims.

In the accompanying drawing:

Figure 1 is a side elevation of our improved safety catch as applied to a base retaining the pointed end of the pin stem.

Figure 2 is a blank showing the body member in extended position slotted through its ears and showing the peripheral bridging arm extended.

Figure 3 is a central sectional view through the blank shown in Figure 2.

Figure 4 is a side elevation of the rotary keeper member.

Figure 5 is a section on line 5—5 of Figure 4.

Figure 6 shows the body member as having been partially bent up from the base to form side ears, said ears being spread sufficiently to permit positioning of the keeper on the trunnion.

Figure 7 shows the ears of the body member as having been closed into operating position.

Figure 8 is a side elevation illustrating the ears of the body and the keeper as having been slotted radially to receive a pin

stem also showing the protuberances on the keeper, one positioned to retain the keeper in open position.

Figure 9 is a section on line 9—9 of Figure 7, showing the keeper in closed position and the protuberances thereon as having been sprung past the bridge member to releasably retain the keeper in closed position.

It is found in the practical construction and operation of safety catches of this character, of advantage to provide a trunnion extending across or bridging the space between the ear members of the body, and to mount the keeper member on this trunnion; also to provide an annular groove in the inner face of one of the ears and to provide an arcuate flange on the keeper extending into this groove, which structure performs two functions; first it provides an extended bearing surface for the keeper and second, it also serves to prevent the keeper from spreading under a radial strain, and, therefore, provides a safety catch of this character with increased strength and adds materially to its essential element of safety which is to prevent the undoing of the catch and the consequent loss of the brooch or valuable pin to which it is attached; and the following is a detailed description of the present embodiment of our invention and showing one construction of safety catch by which these advantageous results may be accomplished:—

With reference to the drawings, 10 designates the opposite side ears of the body member of the catch, which are bent up from the base portion 11. One of these ears is herein shown as being provided with a so-called trunnion member 12 which extends across to bridge the space between the ears 10 when in operating position.

One of these ears, preferably the one carrying the trunnion, is provided with an annular groove, undercut or recess 13 in its inner face.

On this trunnion 12 is rotatably mounted a so-called keeper member 14 which has a central opening 15 to fit onto the trunnion 12, and this keeper member is provided with a laterally extending arcuate flange or projecting portion 16 which extends into the corresponding groove 13 after which the ears 10 of the body member are closed, their faces being substantially parallel with each other, as best illustrated in Figure 7. After

these members have been thus assembled the operating handle 17 of the keeper member is rotated into the position illustrated in Fig. 8, and both the ears, the trunnion and the keeper member are slotted as at 18 for the reception of the pointed end of the pin stem.

When it is desired to close this radial slot to retain the pin stem therein, it is only necessary to swing the handle 17 into the position illustrated in Figure 9.

It is found of advantage to provide simply and effective detent means for releasably retaining the keeper either when in open or in closed position and to accomplish this in a simple and effective way, we have provided a peripheral cross bar 20 which extends across between the ears of the body and we have provided protuberances 21 and 23 on the periphery of the keeper. These protuberances being so located as to pass beneath the bar 20 in the handle 17 as the keeper is moved to open position and when moved to closed position the protuberance 22 swings past the bar 20 to retain the handle in that position.

It is found in practice of advantage to place this peripheral bar 20 in such position as to prevent the operating handle 17 from dropping down onto the base 23 during the soldering operation so as to keep it out of the way while the body is being soldered to the base 23 thereby preventing the handle from also being soldered and so fixed in this position.

Our improved safety catch is very simple and practical in construction and is effective in its operation and by the provision of a laterally-extending flange which projects into the annular groove in the face of the body, the keeper is effectually prevented from spreading under excessive strains to be withdrawn from its trunnion and lost; by which construction the safety elements of the device are greatly improved and by the provision of a plurality of protuberances so placed as to engage and snap under the peripheral cross-bar, the keeper is effectually retained either when in its open position to receive the pin stem or in its closed position to retain the pin stem against accidental removal.

The foregoing description is directed solely towards the construction illustrated, but we desire it to be understood that we

reserve the privilege of resorting to all the mechanical changes to which the device is susceptible, the invention being defined and limited only by the terms of the appended claims.

60

We claim:

1. A safety catch comprising a body member having a pair of spaced side ears, a trunnion on one of said ears bridging said space, the inner face of one of said ears having an annular groove, and a rotary keeper operatively mounted on said trunnion and having a portion extending into said groove.

2. A safety catch comprising a body member having a pair of spaced side ears, a trunnion carried by one of said ears and bridging said space, said ears and trunnion being radially slotted to receive a pin stem, the inner face of one of said ears being provided with an arcuate groove grooved, and a keeper member rotatably mounted on said trunnion and a projecting portion carried by said keeper extending into said groove to increase its bearing surface, said keeper member being slotted to register with the slot in the body ears in one of its positions of rotation.

3. A safety catch comprising a body member having a pair of spaced side ears, a trunnion carried by one of said ears and bridging said space, said ears and trunnion being radially slotted to receive a pin stem, the inner face of the ear carrying the trunnion being provided with an annular groove about the trunnion portion, said slotted keeper member being rotatable in said trunnion and having an arcuate flange extending into said groove whereby the inner and outer bearing surfaces of the keeper are increased and the keeper is supported against spreading under a radial strain.

4. A safety catch comprising a body member having a pair of spaced slotted ears, a peripheral bar bridging the space between said ears, a slotted keeper rotatably mounted between said ears having an operating handle, a plurality of peripheral radial protuberances on said keeper so located as to cooperate with said bar to releasably retain said keeper either in open or closed positions.

In testimony whereof we affix our signatures.

JOHN FIELDING.
JOSEPH P. WHITAKER.
